Primary Examiner — Michael A. Pratt*Assistant Examiner* — Wendy L Arminio*(74) Attorney, Agent, or Firm* — Tommy SF Wang; Want IP Law Group, P.C.(57) **CLAIM**

The ornamental design for a cup lid, as shown and described.

DESCRIPTION

FIG. 1 is a front perspective view of a cup lid showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof; and,

FIG. 9 is another front perspective view thereof with the cup lid shown in a condition of use with a cup, wherein a position of a stopper of the cup lid is changeable.

The broken line portions of the cup lid in FIGS. 1-9 represent unclaimed portions of the claimed design and form no part thereof. The broken lines of the cup in FIG. 9 illustrate unclaimed environment and forms no part of the claimed design.
